REWEAVING MACHINE

Mildred T. Deal, Cleveland, Ohio

Application October 10, 1947, Serial No. 779,055

11 Claims. (Cl. 139—33.5)

1

This invention relates to re-weaving machines and particularly to machines adapted to repair damaged textile fabrics.

The primary object of this invention is to provide a machine which automatically weaves into the fabric over the damage therein a patch of identical material.

Another object is to apply such repair patch so that it is not readily visible to the naked eye.

A further object is to provide an automatic machine of the type stated that is simple and easy to use and which needs relatively little skill or manual dexterity for satisfactory operation.

Still another object is to construct such machine so that it is fast, efficient and economical to use.

These and other objects of the invention will become apparent from a reading of the following specification and claims, together with the accompanying drawings, in which like parts are referred to and indicated by like reference characters and wherein:

Figure 1 is a side elevation, partly in section, of the re-weaving machine;

Figure 2 is a horizontal view, partly in section, of the machine taken along the line and in the direction of the arrows 2—2 of the Figure 1;

Figure 3 is an enlarged side view of a part of the machine, namely the sub-table and plates used to retain and periodically shift the material to be rewoven;

Figure 4 is an enlarged side view of the aforesaid sub-table and plates, together with their operating mechanism;

Figure 5 is a top view of the sub-table and plates shown in the Figure 3;

Figure 6 is an enlarged side view of the latch-type needle used in the machine and part of the holder therefor;

Figure 7 is a vertical sectional view of the needle and holder taken along the line and in the direction of the arrows 7—7 of the Figure 6;

Figure 8 is a plan view of a patch or piece of ravelled woven fabric to be woven into the main fabric;

Figure 9 is a plan view of the patch or piece of fabric shown in the Figure 8 rewoven into the main fabric;

Figure 10 is a side elevation of certain parts of the machine retaining the main fabric and the patch thereon partly rewoven therein; and

Figure 11 is a top plan view of the parts and pieces shown in the Figure 10.

Conducive to a clearer understanding of this invention, it should be noted that a method and

means for manually repairing textile fabrics is disclosed in British Patent 505,010, granted to Alfred and Sarah Ross about May 1, 1939. The method, as disclosed by Ross, shows how a patch of material, the sides of which have been ravelled, is woven into a piece of similar fabric so that the repair is virtually invisible. This British patent also shows the use of a special needle, known as a latch-type needle, for drawing the loose or ravelled patch threads through the fabric. The instant invention is of a machine for doing automatically, fast and sure, what the British patent discloses as having been done manually much slower.

15 Referring to the drawings, there is shown a table 20 designed to conveniently support a garment or large piece of fabric 16 which has a tear or hole 17 therein to be repaired. Mounted on the table there is an upright support 22. This support is hollow and is securely attached to the table by means of the nuts and bolts 23, as shown. 20 Integral with the support 22 there is a forwardly extending arm 24 which is also hollow and contains some of the operating mechanism. This support extends, as shown, over the working portion of the table.

25 Below the top of the table there is a box or support 69 for a small electric motor 68, which is used to drive the re-weaving mechanism.

30 The inside of the vertical support 22 has a bearing bracket 29 to rotatably receive a drive shaft. The inside of the horizontal arm 24 has a slotted bracket 25 and a guide pin 26 for certain herein-after described parts of the needle member. This horizontal arm also has a pair of spaced bearings 39 for a horizontal shaft 45 and worm 46. A large opening or slot 27 is made in the bottom of the horizontal arm 24 in which there moves a depending bar 36 having the latch needle 30 thereon.

35 The latch-type needle 30 used with this machine is clearly illustrated in Figures 6 and 7 and consists of a shank portion 31 and a specially pointed and hooked end 32. At the pointed end 45 32 and just inside the hook there is a small latch 33 pivoted to the needle by means of the pin 34. The latch is made to swing back onto the shank when the needle is inserted into a piece of fabric and to swing forward to close the hook when the needle is withdrawn. Needles of this type are well known in the art.

40 The special needle 30 is firmly mounted in a holder 35 which, in turn, is attached to the depending bar 36. The depending bar 36 projects through the slot 27 and is able to move forwardly

and rearwardly therein. Integral with the bar 36 there is an arm portion 37. This arm portion 37 has a horizontal slot 38 therein which slidably engages the guide pin 26 as is clearly shown in the Figure 1. This arm also slides freely back and forth through the bracket 25. The bracket 25 and the pin 26 guide the arm 37 and depending bar 36 so that the needle 30 attached to the bottom thereof moves longitudinally over the working portion of the table and particularly over the sub-table 50 hereinafter described.

The electric motor 68 has a bevelled gear 40 mounted on its drive shaft. The gear engages and turns a similar gear 41 connected to the vertical drive shaft 42 which extends upwardly through the table top. The top of the shaft 42 is provided with a bevelled gear 43 which engages and turns the fourth bevelled gear 44. The horizontal shaft 45 is connected to the worm 46 mounted between the bearings 39. This worm 46 rotates a small worm gear 47 axially mounted on the inside wall of the horizontal support 24. A small arm 48 is linked to the slotted arm 37 by means of the two pins 49. The small link 48 is mounted off center on the worm gear 47 so that rotation of the worm gear will cause the arm 37 to reciprocate longitudinally in the horizontal support 24.

The table member 20 has a hole therein at its work portion and in this hole there is mounted a small block of wood or metal referred to and indicated herein as a sub-table 50. The sub-table 50 has a rough or serrated top surface 51 which is normally on a plane with the top of the table member 20. This top surface is made rough or serrated in order to better engage the fabric 16. Across the top of the sub-table 50 there is a groove or channel 55 which is aligned with the latch needle 30. This groove is slightly wider than the needle and when the sub-table is raised as hereinafter described, it does not obstruct the free reciprocal longitudinal movement of the needle which is normally close to the surface of the table top. The bottom of the sub-table 50 has an arm 52 thereon which engages a small crank element 53. This crank element 53 is connected to a gear train 54 which, in turn, is connected to the motor 68. Rotation of the motor causes the crank element 52 to raise and lower and to move laterally the sub-table 50 periodically.

At the sides of the sub-table 50 there are plates 60 which have teeth 61 on the top edges thereof as shown. The front and back plates 60 are connected together at the ends of the sub-table 50 so that they practically enclose or surround the sub-table. The connecting members are indicated by the reference character 66. Each side plate 60 also has a notch 65 at the top edge thereof which is in line with the groove 55 in the sub-table 50. These notches 65 permit the needle 30 to project unobstructively through the plates and sub-table.

The bottom of each of the connected plates has a horizontal slot 62 which engages a second crank element 63. This second crank element 63 is connected to a gear train 64 which is also connected to the motor 68 in a way which causes the two parallel plates 60 to be moved up and down periodically as shown in the Figure 3.

Mounted on the horizontal arm or support 24 there is a depending arm 28 and bracket 71 which supports a comb 70. This comb is mounted at an incline directly over the sub-table 50. The depending bracket 71 is connected to the arm 28 by means of a pintle pin 72 and is allowed to

swing laterally in a small arc with the herein-after described fabric and patch 16 and 18 respectively.

To use this device, the fabric 16 to be repaired or rewoven is placed on the table 20 so that the hole or damage therein is directly over the sub-table 50, with either the warp or weft of the fabric running parallel with the serrations of the sub-table or in line with the needle. A patch 18 of similar material slightly larger than the hole 17 is prepared. This is done by ravelling the four sides thereof to form a patch somewhat as shown in the Figure 8. This patch 18 is matched with the fabric 16 so that the weave or pattern is juxtaposed. The loose threads of the near ravelled edge 19 are inserted in the comb 70 in an orderly and regular manner. Both the fabric 16 and the patch are held down on the sub-table near the end plates 60. The motor 68 is set in operation and the plates 60 are caused to move up and down slightly. Simultaneously the needle 30 is caused to move forward and thus passes in and out of the fabric 16 in a manner similar to a darning operation.

At the end of the forward movement and while the needle 30 is still in the fabric, the small hook 32 at the point thereof engages a thread 19 in the comb 70. This thread is pulled out of the comb and drawn into the fabric 16. When the needle 30 reaches its maximum rearward position, it stops momentarily and the sub-table 50 moves to one side the distance of one tooth of the comb. The sub-table 50 then drops below the top surface of the plates 60 or to the place of beginning. This somewhat rotary motion moves the fabric and patch so that they are properly positioned to receive another insertion of the needle 30. This is repeated until all of the loose threads on that side of the patch are woven into the fabric. The fabric and patch are then turned or positioned so that the other three sides of the patch are similarly rewoven into the fabric. After all four sides of the patch are thus woven, the loose ends thereof are trimmed on the underside of the fabric and loose ends of the fabric at the hole are cut off. When finished, the patch blends with the fabric and the place of attachment is hardly visible.

As the fabric and patch, 16 and 18 respectively, move sideways automatically the comb 70 attached to the swinging bracket 71 moves with it so that a new loose thread of the patch is properly positioned in front of the needle 30 and so that a new thread or strand of the patch may be engaged and drawn through the fabric in a straight line. The arc of the swing is only a small number of degrees and the lateral swing or movement of the comb 70 is also short, roughly about one inch. If a large patch is to be applied to the fabric, the fabric and patch are then repositioned to move through two or more swings or movements of the comb as may be necessary.

It should be pointed out that the various movements of the needle, the sub-table and side plates are properly timed and synchronized so that the reweaving operation is smooth and continuous. It should be understood that the device as illustrated and described is somewhat schematic, but it should also be understood that minor changes in structure, especially those relating to the orderly synchronous movement of the parts, is simply a matter of design well within the knowledge of persons skilled in the machine weaving or sewing art.

Having thus broadly disclosed the invention

in its preferred form, it should be further understood that no limitations thereof are intended except those imposed by the scope of the appended claims.

I claim:

1. A re-weaving machine, comprising in combination, a table member supporting a piece of fabric to be rewoven, an oscillating member mounted on the table member and capable of intermittently raising and lowering the said piece of fabric, a comb member mounted on the table member and supporting a patch, the ravelled ends of which are to be woven into the said piece of fabric, and a latch-type needle mounted on the table member movable in and out of the said oscillated fabric and engageable with a thread of the patch and capable of drawing it through the fabric.

2. A re-weaving machine, comprising in combination, a table member supporting a piece of fabric to be rewoven, a pair of spaced plate members mounted on the table member and capable of raising and lowering the said piece of fabric, a comb member mounted on the table member and supporting a patch, the ravelled ends of which are to be woven into the said piece of fabric, and a latch-type needle mounted on the table member movable in and out of the said oscillated fabric and engageable with a thread of the patch and capable of drawing it through the fabric.

3. A re-weaving machine, comprising in combination, a table member supporting a piece of fabric to be rewoven, a comb member mounted on the table member and supporting a patch, the ravelled ends of which are to be woven into the said piece of fabric, a latch-type needle mounted on the table member movable in and out of the said fabric and engageable with a thread of the patch and capable of drawing it through the fabric, and an oscillating means mounted on the table member and capable of positioning the piece of fabric with respect to the movable needle to cause the needle to move in and out therethrough.

4. A re-weaving machine, comprising in combination, a table member supporting a piece of fabric to be rewoven, an oscillating member mounted on the table member and capable of intermittently raising and lowering the said piece of fabric, a comb member mounted on the table member and supporting a patch, the ravelled ends of which are to be woven into the said piece of fabric, a latch-type needle mounted on the table member movable in and out of the said oscillated fabric and engageable with a thread of the patch and capable of drawing it through the fabric, and a means for laterally advancing the piece of fabric on the oscillating member the space of one strand of the patch.

5. A re-weaving machine, comprising in combination, a table member supporting a piece of fabric to be rewoven, an oscillating member mounted on the table member and capable of intermittently raising and lowering the said piece of fabric, a comb member mounted on the table member and supporting a patch, the ravelled ends of which are to be woven into the said piece of fabric, a latch-type needle mounted on the table member movable in and out of the said oscillated fabric and engageable with a thread of the patch and capable of drawing it through the fabric, and a sub-table member having means for engaging and advancing the piece of fabric on the table member.

6. A re-weaving machine, comprising in combination, a table member supporting a piece of fabric to be rewoven, an oscillating member mounted on the table member and capable of intermittently raising and lowering the said piece of fabric, a comb member mounted on the table member and supporting a patch, the ravelled ends of which are to be woven into the said piece of fabric, a latch-type needle mounted on the table member movable in and out of the said oscillated fabric and engageable with a thread of the patch and capable of drawing it through the fabric, and a movable sub-table member having serrations engageable with the fabric and capable of advancing it a distance corresponding to the width of one strand of the patch.

7. A re-weaving machine, comprising in combination, a table member supporting a piece of fabric to be rewoven, a pair of spaced plate members mounted on the table member and capable of raising and lowering the said piece of fabric, a comb member mounted on the table member and supporting a patch, the ravelled ends of which are to be woven into the said piece of fabric, a latch-type needle mounted on the table member movable in and out of the said oscillated fabric and engageable with a thread of the patch and capable of drawing it through the fabric, and a sub-table member having serrations engageable with the fabric and capable of advancing it a distance corresponding to the width of one strand of the patch.

8. A re-weaving machine, comprising in combination, a table member supporting a piece of fabric to be rewoven, a comb member mounted on the table member and supporting a patch, the ravelled ends of which are to be woven into the said piece of fabric, a latch-type needle mounted on the table member movable in and out of the said fabric and engageable with a thread of the patch and capable of drawing it through the fabric, an oscillating means mounted on the table member and capable of positioning the piece of fabric with respect to the movable needle to cause the needle to move in and out therethrough, and a sub-table member having means for engaging and advancing the piece of fabric on the table member.

9. A re-weaving machine, comprising in combination, a table member supporting a piece of fabric to be rewoven, a pair of spaced plate members mounted on the table member and capable of raising and lowering the said piece of fabric, a comb member mounted on the table member and supporting a patch, the ravelled ends of which are to be woven into the said piece of fabric, a latch-type needle mounted on the table member movable in and out of the said oscillated fabric and engageable with a thread of the patch and capable of drawing it through the fabric, a movable sub-table member having serrations engageable with the fabric and capable of advancing it a distance corresponding to the width of one strand of the patch, and a motor including a cam device raising and lowering the pair of spaced plate members and moving the sub-table member in coordination with the movement of the said needle.

10. A re-weaving machine, comprising in combination, a table member supporting a piece of fabric to be rewoven, a pair of spaced plate members mounted on the table member and having means for shifting the position of the piece of fabric, a comb member mounted on the table member and supporting a patch, the ravelled ends of which are to be woven into the said piece of

fabric, and a latch-type needle mounted on the table member movable in and out of the said oscillated fabric and engageable with a thread of the patch and capable of drawing it through the fabric.

11. A re-weaving machine, comprising in combination, a table member supporting a piece of fabric to be rewoven, a comb member mounted on the table member and supporting a patch, the unravelled ends of which are to be woven into the said piece of fabric, a latch-type needle mounted on the table member movable in and out of the

said fabric and engageable with a thread of the patch and capable of drawing it through the fabric, a first oscillating means mounted on the table member capable of positioning the piece of fabric with respect to the movable needle to cause the needle to move in and out therethrough, and a second oscillating means mounted on the table member capable of shifting the piece of fabric and the patch thereon the distance of one thread thereof.

MILDRED T. DEAL.
